UNITED STATES PATENT OFFICE.

ALEXANDER McDougall, OF DULUTH, MINNESOTA.

JURY-RIGGED SAIL FOR SHIPS.

1,243,198.

Specification of Letters Patent. Patented Oct. 16, 1917.

Application filed October 26, 1916. Serial No. 127,907.

To all whom it may concern:

Be it known that I, ALEXANDER McDougall, a citizen of the United States, residing at Duluth, in the county of St. Louis 5 and State of Minnesota, have invented certain new and useful Improvements in Jury-Rigged Sails for Ships, of which the following is a specification, reference being had therein to the accompanying drawing.

This invention consists of certain improvements in auxiliary propelling means for vessels and relates particularly to a set of jury rigged sails for such purpose, they being especially applicable to ships having flat 15 decks free from high hatch coamings, deck winches, bulwarks or other obstructions which might interfere therewith.

The object is to provide a novel device of this character which is readily accessible 20 either in emergency or for auxiliary means of propulsion, one that may be easily manipulated by hand and occupy the least space possible when stowed away.

Another object is to provide a form of 25 jury rigged sails that requires no stays, shrouds or support other than a mast and which may be adjusted wholly by hand.

Other objects and advantages will appear in the further description of the invention.

In the accompanying drawings forming 30 part of this application and in which like letters of reference indicate like parts:

Figure 1 is a side elevation of a flat decked vessel equipped with my invention.

Fig. 2 is a top plan view of same.

Fig. 3 is a midship cross sectional view of the ship.

Fig. 4 is a vertical sectional view through one of the mast sockets.

Fig. 5 is an enlarged elevation of one of the masts having mounted thereupon one of the sails partly reefed, and

Fig. 6 is a view of one of the masts having mounted thereupon a sail wholly rolled up and ready for stowing away.

1 represents the deck of the vessel in which are numerous hatches 2 and which hatches are covered by suitable plates 3, these latter, when in place being bolted down upon a low 50 flat coaming 4 by suitable bolts 5, which construction appears in patents previously granted to me and known in the art.

In the preferred arrangement of my jury-rigged sails, I place a mast step or socket 6 at each forward or after corner, as desired, of the hatches, the base of the socket being

formed with an elevated projecting flange 7 of the proper height to rest upon the hatch cover 3 and to be bolted therethrough by one of the hatch bolts 5. Upon the opposite side 60 of the socket and flush with the bottom thereof is a flange 8 which rests upon and is bolted directly to the deck 1 by a suitable bolt 9. By putting the socket adjacent the hatches and utilizing one of the hatch bolts for holding same, the necessity for more numerous holes in the deck of the vessel is avoided and what holes are formed therein as for the bolts 9, may be kept closed 65 either by wooden plugs or the bolts themselves, if desired, when the sockets are not in place.

The sockets 6 are preferably made larger at the top than at the bottom and the butt of the masts 11 tapered to snugly fit therein 75 and are retained by means of suitable through bolts 10 which pass entirely through both the mast and socket so as to make a stout and secure footing for the mast requiring no shrouds or stays whatever for additional support.

An eye 12 is formed upon the forward side of each socket 6 for convenient attachment of the sheet or clue line of the next sail forward and a convenient cleat 13 is formed 85 upon the opposite side and which may be used in the shipping and unshipping of the masts.

The masts 11 are tapered from the top of the steps to their upper ends and are, as compared with the usual masts for such vessels, 90 comparatively short and stubby.

Each mast is fitted with a triangular shaped, or leg of mutton sail 15 tightly fitted thereto and without halyards or attachments 95 other than tight lashings about the mast as illustrated at 14, and which secure fastening of the sail to the mast is for the purpose of permitting the sail to be clued about the mast for shortening it in lieu of reefing, and 100 this is accomplished by passing the leach of the sail about the mast one or more times as desired, and the sail being thus wound up about the mast results in reducing its area to the force of the wind and obviates the necessity of reef points and their use, the foot of the sail being inclined upwardly toward the 105 clew, to clear the deck well.

A still further object of the sail and mast being securely united is to permit of the 110 former being entirely wound up upon the latter for stowing away when not in use.

It is evident that the mast sockets may or may not be placed upon the deck at the beginning of a voyage, depending entirely upon the conditions anticipated by the 5 navigator and that the only provision whatever necessary in the construction of an ordinary ship's hull for the utilization of my improved auxiliary device is the addition of a single hole in the deck of the 10 ship for each jury mast socket.

Thus I have provided an extremely simple and convenient auxiliary means for making available to a ship while at sea, the power of the wind, either in addition to 15 other forms of propulsion or as provision against ship wreck or loss in the event of accident to the other form of propulsion used, and that without the accompanying danger of lofty rigging, et cetera, as where 20 the ordinary sail equipment is used.

Having thus described my invention what I claim as new and desire to secure by Letters Patent, is:

1. The combination with a ship of a plurality of portable mast sockets, masts having their bases tapered to snugly fit within the sockets, means for holding the mast against rotation and leg of mutton sails tightly lashed to the masts in such a manner 25 as to be shortened by winding the sail about the mast.

2. The combination with a ship, of a plu-

rality of portable mast sockets, masts having their bases tapered to snugly fit within the sockets, means to prevent the masts revolving in the sockets, and leg of mutton sails securely lashed to the masts in such a manner as to be shortened by winding the sails about the mast, substantially as and for the purpose set forth.

35

3. The combination with a flush decked vessel having low flat hatches, of mast sockets designed to overlap and be temporarily fitted to opposite corners athwartships of each hatch, portable masts having leg of mutton sails tightly lashed thereto and designed to be wholly supported by the sockets.

40

4. The combination with auxiliary propelling means for ships comprising a triangular shaped sail lashed tightly to a portable mast and means for securing the mast without shrouds or stays to the deck of the ship, of means for securing the mast against rotation whereby the exposed area of the 45 sail may be reduced by winding it about the mast.

50

In testimony whereof I hereunto affix my signature in the presence of two witnesses.

ALEXANDER McDougall.
